UNITED STATES PATENT OFFICE

WILLIAM F. OBERHUBER, OF EAST LANSDOWNE, PENNSYLVANIA

APPARATUS FOR CLEANING CONDENSER TUBES

Application filed July 3, 1922. Serial No. 572,570.

My invention relates to cleaning condenser tubes and to the slugs or plugs which are passed through the tubes to perform the cleaning operation.

5 A main purpose of my invention is to progressively discharge fluid within the tube ahead of an advancing cleaner, slug or plug.

A further purpose is to expand the slug or plug into wiping contact with the interior 10 of the tube by the driving fluid.

A further purpose is to permit limited 15 passage of the driving fluid through the cleaning slug or plug so as to insure ejection of the plug or slug if the tube becomes closed ahead of it.

A further purpose is to swell the rear portion 20 of the slug during its passage through the tube by fluid pressure, maintaining it in tight contact with the interior of the tube and increasing the contact with any slowing up of the slug or plug by reason of its engaging excessive dirt within the tube.

A further purpose is to provide a slug or 25 plug with an aperture through it so that part of the fluid by which the slug or plug is driven passes through the plug or slug. I may taper a central aperture so as to improve the quality as a nozzle or may direct diagonally against the interior wall one or more 30 streams to better break up the coating of dirt and separate it from the tube wall.

A further purpose is to combine the aperturing of the slug or plug with the expansion 35 of the rear part or—and—body of the slug so as to obtain both the flow through the slug upon which the success of my invention primarily depends and the outward swelling of the slug.

A further purpose is to give flexibility to 40 the slug or plug and to the cupping at its rear.

A further purpose is to form a rearwardly facing cup upon the tube of the slug or plug and to support it by the body to prevent it from turning inside out.

45 Further purposes will appear in the specification and in the claims.

I have preferred to illustrate my invention by a few forms only among many by which it may be presented, selecting forms which are 50 practical, efficient and fully effective and

which at the same time will illustrate the principles of my invention.

Figure 1 is a perspective view showing one form of my invention.

Figure 2 is a reduced-scale longitudinal 55 section of the device seen in Figure 1.

Figure 3 is a perspective view showing a second form of my invention.

Figure 4 is a reduced-scale longitudinal 60 section of the device seen in Figure 3.

Figures 5 and 6 are central longitudinal sections of other forms of my invention.

Figure 7 is a section of a condenser tube in which the slug of Figure 6 is shown.

Figure 8 is a top plan view of a slug carrying metal scrapers.

Figure 9 is a section of Figure 8 upon line 9—9.

Figure 10 is a section similar to Figure 9 but of another form.

In the drawings similar numerals indicate like parts.

It is desirable to clean condenser tubes nightly in order that the slime, sediment, etc., 75 for convenience herein called dirt, which has accumulated upon the inside of the tubes may be removed so that the efficiency of heat transfer through the tubes may be maintained at a maximum.

Though it is not new to pass plugs, known 80 in the art as slugs, of resilient material, usually rubber, through condenser tubes by air or water pressure and to thus rub off and remove a considerable part of the dirt within the tubes, my invention disclosed herein has increased the efficiency of the operation by approximately 40 per cent in quantity, removing also that part of the coating closest to the tubes left by the previously existing slugs and securing contact of the contents of the tube with the metal of the tube itself which much 85 further increases the efficiency of heat transfer.

Referring to the forms illustrated, in explanation and not in limitation:—

In Figure 1, the middle portion of the slug 5 is necked at 6 and the neck is connected preferably by curved shoulders at 7 with annular flanges or rims 8, 8' which are intended to en- 100

gage and rub the interior walls of the tubes so as to wipe them clean.

Whichever the direction of movement—and except for the tapering of the aperture it makes no difference in this form—the leading edge, preferably 9, performs some scraping function but the firmest engagement is made by the trailing edge, in that case 10. The outer end faces are annular at 13. The edges 11 and 12 are also helpful, according to the direction of movement. Both ends are cupped at 14 so that the fluid pressure may be effective on the rear to press the rear portion of the corresponding cylindrical rim 8 or 8' outwardly against the interiors of the tubes.

The cylindrical rim 8 gives a long tube engaging surface. This fact and the stiffening of the tube by the fillet at 7 would be sufficient to prevent turning of the end cup at 14 wrong side out. They very effectively maintain the shape of the cup for the purpose engaged.

The aperture through the slug is preferably tapered so as to produce an effective nozzle. In the illustration the larger end of the aperture is shown at the rear which will project the discharge a considerable distance into the tube before the fluid spreads sufficiently to engage the interior walls of the tube. This extends the distance between the slug and the point where the fluid makes impact with the interior walls of the tube but produces the best results as it considerably increases the velocity of the fluid and the consequent cleansing effect of the jet.

On the other hand if the slug be passed through the tube with the smaller end of the tapered opening at the rear, along with lower velocity of fluid through the nozzle is obtained a quicker distribution of the fluid against the walls of the tube, causing engagement of the fluid with the tube walls closer to the advancing slug.

In use, the slug is inserted within one end 45 of a tube such as 17 to be cleaned and the nozzle by which the driving fluid pressure is applied, usually air or water, is pressed against or within the end of the tube to apply the pressure back of the slug. The slug is expanded bodily, (if the larger end of the tapered opening be at the rear) but particularly at the cupped rear end by reason of the pressure against the interior walls.

As the slug is moved through the tube by 55 fluid pressure at the rear a portion of the fluid supplied under pressure passes through the aperture or "nozzle" through the body of the slug and impinges (at a distance depending upon the predetermined character of nozzle formed) against the interior of the tube, loosening and removing a considerable part of the dirt within the tube before the slug reaches it.

Where the dirt is dry it may be effectively 65 moistened and loosened in this way in ad-

vance of the slug by driving the slug by water pressure.

As will be seen not only does the slug perform the function of prior imperforate slugs used in this art of wiping the interior surface of the tube but it provides an advancing nozzle by which successive sections of the tube ahead of the plug are preliminarily cleaned and may preliminarily also be moistened, reducing the amount of work left for the slug.

The aperturing of the slug not only provides an advancing jet nozzle and allows the slug to be swelled outwardly in its entirety, assisting the cupping in securing maximum pressure of the slug against the interior walls of the tubes, but it also provides additional resilience for radial compression of the slug so that it may pass obstacles or to permit use of the same slug in a larger range of tube diameters.

When air pressure is used to drive the slug through the tubes, the aperturing of the slug secures a further advantage, in that if the tube ahead of the slug becomes clogged, the slug automatically will be driven back and out of the tube as soon as the air pipe is removed, thus giving direct access to the clogged portion of the tube.

As a reason for this, when a tube becomes clogged ahead of the slug there is almost immediately full air pressure ahead of the slug, after which there is no further tendency toward driving the plug into the obstruction, air pressure on both sides of the slug being the same. When the air pipe is taken away, suddenly releasing the pressure back of the slug, the air trapped in front of the slug suddenly expands driving the slug ahead of it out of the tube, the aperture through the slug being too small to instantly release the pressure.

In practice I have secured excellent results with quite small apertures, as one fifth of the diameter of the slug, with which the nozzle is very effective and the driving pressure is not noticeably reduced.

While in practice I much prefer to aperture the slug so as to secure the double advantage of the expansion to close contact with the tube and of the cleaning blast through the slug, it may under certain conditions be desired to avoid the blast of fluid through the slug, and I show in Figures 3 and 4 a form adapted to meet this condition, the slug shown being like that of Figures 1 and 2 with the exception that while the slug is internally hollowed at 15' from the rear end to give expansion to close contact with the tube, this internal hollow does not pass through the slug and the blast through the slug is thus avoided. This form may be used substantially the same as that of Figures 1 and 2, and like that form may be sent through the tube with either end forward, the mere cupping of the end being sufficient to give expansion to close contact with the tube, though

less efficiently than with the internal hollow 15'.

5 The form shown in Figure 5 is used the same as that of Figures 1 and 2 and presents the same benefits of a cleaning blast in front and expansion to close contact with the tubes.

10 When more than one aperture or nozzle is to be used I get the best results by forming the nozzles from a common central opening.

15 In the form of Figures 6 and 7, there are a plurality of inclined nozzles 18 from the internal hollow 15', spaced circumferentially about the plug and adapted to discharge a plurality of cleaning blasts against the walls of the tubes at an angle sufficiently steep to penetrate the dirt and loosen it more fully from the tube walls ahead of the slug.

20 In the form shown in Figures 8 and 9 the slug is of the same character as that shown in Figure 1 but the rear rim 8' is provided with inset metal scraping surfaces in the form of wire loops 20 anchored within the body of the slug by prongs 21. The loops are shown as arranged in annular rows which overlap, the central portions of the loops of one row spanning the ends of the loops of the next.

30 In Figure 10 the same general form is shown but plates 20' are used instead.

35 In both forms the metal scraping surfaces are pressed outwardly against the interior of the tube which is being cleaned by the pressure of the driving fluid. The metal scrapers perform their function without interference with the wiping action of the adjoining rubber.

40 The directions of motion of the different slugs are indicated by the arrows on the figures.

45 Other forms of my invention will occur to those skilled in the art which secure all or a part of the benefit of the invention but which depart from it according to the whim of the designer or his desire to avoid the use of the forms illustrated by me; and it is my intention to include herein all such other forms that may come within the reasonable spirit and scope of my claims.

50 Having thus described my invention, what I claim as new and desire to secure by Letters Patent is:

1. A rubber slug for use in cleaning condenser tubes by passage through the tubes and scraping engagement with their walls having a free central longitudinal passage to allow pressure discharge of the fluid through it.

60 2. A rubber slug for use in cleansing condenser tubes by passage through the tubes and scraping engagement with their walls, provided with a central tapered passage lengthwise of the slug to permit and direct 65 fluid passing through it.

3. A rubber slug for use in cleansing condenser tubes by passage through the tubes and scraping engagement with their walls, having a concave rear end and a central longitudinal passage to allow flow of fluid 70 through the slug.

4. A slug for cleaning condenser tubes, comprising an elongated body of rubber having approximately the same diameter at both ends, said plug being of reduced diameter between the ends and having a central aperture flaring at the rear as compared with the front end. 75

5. A tube for cleaning condenser pipes comprising a rubber body centrally apertured, the aperture tapering toward its front end to permit flow of fluid through the body and to converge the lines of such flow. 80
